(57) **CLAIM**

The ornamental design for a payment card chip, as shown and described.

DESCRIPTION

FIG. 1 is a front left perspective view of a payment card chip showing our new design; and,

FIG. 2 is a front elevation view thereof.

The broken lines of even length shown in the drawings illustrate portions of the payment card chip that form no part of the claimed design. The broken lines of uneven length show the unclaimed boundary of the claimed design.
